[57] CLAIM

The ornamental design for the safety strap for use in a vehicle seat, as shown as described.

DESCRIPTION

FIG. 1 is a side elevational view of the safety strap for use in a vehicle seat showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view thereof; and

FIG. 7 is a perspective view showing the safety strap for use in a vehicle seat in use.

The chair shown in broken lines in FIG. 7 is for illustrative purposes only.
